UNITED STATES PATENT OFFICE.

HANS P. DAHLSTRAND, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

TURBINE SYSTEM.

Application filed September 20, 1920. Serial No. 411,552.

This invention relates in general to improvements in the construction and operation of energy translating apparatus, and relates specifically to improvements in power systems for converting the potential energy of an agency such as steam, into kinetic energy, with the aid of a prime mover such as a steam turbine or like apparatus.

An object of the invention is to provide an energy translating device which is simple in construction and which will produce high economy in operation.

It has been found desirable in certain commercial installations such as paper, woolen and rubber mills, to employ steam or other heating agencies at a predetermined pressure and temperature, for the purpose of heating auxiliaries such as rolls, driers and the like. The pressure and temperature at which it is desirable to utilize the heating agency is ordinarily below that of the agency at the source of generation. Considerable loss in available energy results from merely reducing the pressure and temperature of the agency by means of a throttle valve or similar device. When utilizing a throttle valve to so reduce the pressure and temperature of steam, the excess heat is dispersed in super-heating the agency during reduction in the pressure thereof. It is also a fact that where a heating agency such as steam is employed to heat auxiliaries, the steam which leaves the auxiliaries or heating system still possesses considerable available energy.

In order to effect complete utilization of all of the available energy in the heating agency employed in such installations, the present invention contemplates the provision of means for converting into useful work substantially all the potential energy of the agency, including the excess energy which is not utilized in the auxiliaries.

To effectively accomplish this result at minimum initial cost of installation, the present invention further contemplates utilization of standard apparatus to convert the excess energy into useful work. The present invention further contemplates the provision

of means for controlling characteristics of the agency during conversion of its energy in the system.

Additional objects and advantages of the present invention will appear in the course of the following description.

A clear conception of an embodiment of the invention and of the operation of the device, may be had by referring to the drawing accompanying and forming a part of this specification, in which like reference characters designate the same or similar parts in the several views.

Figure 1 is a central vertical section through a steam turbine of the ordinary high-pressure condensing type, in which the energy of the steam passing through the turbine is converted into useful work, by increments.

Figure 2 represents a turbine similar in construction to the turbine disclosed in Figure 1, but differing from the turbine of Figure 1 in that an intermediate stage has been removed and a dividing diaphragm or wall substituted, the chambers on opposite sides of this diaphragm having been connected to heat utilizing apparatus.

While the invention is disclosed herein as applied to a turbine of the reaction type, it is obvious that the same is applicable to turbines of other types as well as to other forms of heat engines.

The turbine disclosed in Figure 1 comprises in general a rotary spindle 2, mounted in bearings 3, and enclosed within a stationary casing 4. The turbine spindle has a plurality of rings of buckets or blades which coact with stationary rings of blading mounted in casing 4 to abstract energy from the steam passing through the turbine. The high pressure steam is admitted to the casing 4 through a control valve 5 and is delivered from the turbine to the condenser through an exhaust passage 6. The turbine spindle 2 is provided with a balance piston 7 which counter-balances the end thrust induced by the steam flowing toward the exhaust end of the turbine.

The turbine disclosed in Figure 2 differs

from that of Fig. 1 only in that the intermediate stage 8 of the turbine of Figure 1, has been eliminated and the casing 4 has been formed with an enlarged portion 80 having a diaphragm 9 associated therewith which divides the turbine into two parts. The chamber 10 on the side of the diaphragm nearest the turbine inlet, connects with a pipe or conduit 11 leading to a heat utilizing device 12. The discharge end of the heat utilizing device 12 connects with the chamber 13 on the side of the diaphragm 9 nearest the exhaust end of the turbine, through a pipe or conduit 14 and a back pressure valve 15. A drain pipe 16 which connects with a separator located near the discharge end of the heat utilizing device 12 permits discharge of water of condensation from the steam delivered to the conduit 14.

The back pressure valve 15 is provided with a pressure piston 17 and an adjustable spring 18, whereby the valve may be set so that it will open only when a pre-determined pressure is attained on the side of the valve associated with the heat utilizing device 12. With the exception of the omission of the intermediate stage 8 and the substitution of the diaphragm 9 and chambers 10, 13, the turbine of Figure 2 is identical with the turbine of Figure 1. The drop in pressure resulting by the passage of steam through the heat utilizing device 12 is substantially equal to the drop in pressure resulting from the passage of steam through the stage 8 of the turbine disclosed in Figure 1. The joint between the diaphragm 9 and the turbine spindle 2 is provided with packing 19 which prevents direct passage of steam from the chamber 10 to the chamber 13.

During normal operation of the turbine disclosed in Figure 1, the steam is admitted through the controlling valve 5 and after passing through the turbine blading is delivered to the condenser through the exhaust chamber 6. The energy of the steam is converted into useful work by rotating the spindle 2 of the turbine.

During the normal operation of the turbine disclosed in Figure 2, the steam is admitted to the high pressure section of the turbine through the controlling valve 5 and after having a part of its energy abstracted is delivered into the chamber 10. From the chamber 10 all of the steam passing through the high pressure section of the turbine is delivered to the heat utilizing device 12 through the pipe or conduit 11. After having another portion of its energy converted in the heat utilizing device 12, all of the steam which remains, is delivered to the chamber 13 through the pipe or conduit 14 and the back pressure valve 15. The back pressure valve 15 serves to control the pressure of the steam admitted to the chamber

13, the delivery pressure depending upon the setting of the spring 18. From the chamber 13 the steam passes through the low pressure section of the turbine and is eventually delivered to the condenser through the exhaust chamber 6.

It will thus be noted that regardless of the initial pressure of the steam at the source of generation, the apparatus embodying the present invention permits substantially complete utilization of all of the available energy in the steam and further makes available a sufficient supply of steam for the auxiliaries at the desired pressure and temperature. The cost of installation is reduced to a minimum by utilizing standard turbine parts, the efficiency of which is maintained substantially constant by the provision of a back pressure valve which controls the pressure of the steam admitted to the low pressure portion of the turbine. The temperature and pressure of the steam delivered to the heat utilizing device 12 may be readily varied by merely varying the characteristics of the steam admitted to the turbine with the aid of the controlling valve 5. Such variation in the characteristics of the steam supplied to the turbine will affect the delivery of power, but as an installation of this kind is ordinarily desirable in plants where several generators are operated in parallel, variations in the power output of the turbine embodying the present invention will not be undesirable.

It should be understood that it is not desired to limit the invention to the exact details of construction and of operation of the apparatus herein shown and described, for various modifications within the scope of the claims may occur to persons skilled in the art.

It is claimed and desired to secure by Letters Patent:—

1. In combination, a turbine comprising a single casing and a rotor therein, said turbine being devoid of intermediate stage blading of known characteristics, a partition located at the place of omission of said blading and dividing said turbine into two parts, heat utilizing device having a heat absorption capacity equal to that of said omitted blading, said device communicating with said turbine on opposite sides of said partition, and means automatically operable by the pressure at the discharge from said device to control the admission of fluid from said device to said turbine.

2. In combination, a turbine comprising a single casing and a rotor therein, said turbine being devoid of intermediate stage blading of known characteristics, a partition located at the place of omission of said blading and dividing said turbine into high and low pressure parts, a heat utilizing de-

vice having heat absorption capacity equal to that of said omitted blading, said device receiving all of the fluid entering said turbine from the discharge end of said high pressure part and returning said fluid at a lower tension to the inlet end of said low pressure part, and a valve automatically op-

erable by the pressure at the discharge from said device to control the admission of fluid to the inlet of said low pressure part. 10

In testimony whereof, the signature of the inventor is affixed hereto.

HANS P. DAHLSTRAND.
